[57] CLAIM

The ornamental design for a fishing pole holder, as shown and described.

DESCRIPTION

FIG. 1 is a side elevational view of the fishing pole holder, showing my new design of the present invention;

FIG. 2 is an opposite side elevational view thereof; FIG. 3 is a rear elevational view of the fishing pole holder as seen from the left hand side of FIG. 1;

FIG. 4 is a front elevational view thereof;

FIG. 5 is a top plan view thereof; and

FIG. 6 is a bottom plan view of the fishing pole holder.
